UNITED STATES PATENT OFFICE.

THEODORE G. LEWIS, OF BUFFALO, NEW YORK, ASSIGNOR TO THE BUFFALO DENTAL MANUFACTURING COMPANY, OF SAME PLACE.

DENTAL ARTICULATOR.

SPECIFICATION forming part of Letters Patent No. 659,871, dated October 16, 1900.

Application filed July 9, 1900. Serial No. 22,945. (No model.)

To all whom it may concern:

Be it known that I, THEODORE G. LEWIS, a citizen of the United States, residing at Buffalo, in the county of Erie and State of New York, have invented new and useful Improvements in Dental Articulators, of which the following is a specification.

This invention relates to anatomical or dental articulators in which the hinged upper jaw-plate is capable of a lateral and a forward-and-backward movement in a horizontal plane. An articulator of this kind is shown and described in Letters Patent of the United States No. 547,195, granted October 1, 1895, to Robert H. Antes, and my invention relates more especially to improvements in said articulator.

The objects of my invention are to simplify and improve the construction of the devices which yieldingly hold the upper plate in its normal central position, to provide a simple lock or catch for reliably holding the upper plate in an upright position, to provide said plate with convenient means for oscillating it when testing a case for occlusion, and finally to improve the means for adjusting the upper plate vertically to accommodate casts of different thicknesses.

In the accompanying drawings, Figure 1 is a side elevation of my improved articulator. Fig. 2 is a front view thereof. Fig. 3 is a top plan view of the same, partly in section. Fig. 4 is a central longitudinal section of the rear portion of the articulator on an enlarged scale. Fig. 5 is a fragmentary longitudinal section of the articulator, on an enlarged scale, showing the upper jaw-plate locked in its raised or upright position. Fig. 6 is a horizontal section, on an enlarged scale, in line 6-6, Fig. 2.

Like letters of reference refer to like parts in the several figures.

A is the base or lower jaw-plate of the articulator, and B the upper vertically-swinging jaw-plate, which is secured centrally to the yoke or upper bracket C. This yoke is hinged by horizontal pivot-pins d to the upwardly-extending ends of a lower bracket D, which is secured to a standard E, rising from the rear portion of the lower jaw-plate A.

The outer portions of the pivot-pins d are preferably screw-threaded and engage in

threaded openings of the lower bracket D, while the inner portions of the pins enter longitudinal slots f, formed in the ends of the yoke C, as shown in Fig. 3. This connection permits an endwise or forward-and-backward movement and also a lateral or oscillating movement of the yoke and the upper jaw-plate for testing the occlusion of the teeth in a well-known manner.

g is a longitudinal barrel or casing mounted rigidly on the rear portion of the yoke or upper bracket C and preferably formed integral therewith. This casing is open at its rear end and closed at its front end.

h is a guide-rod passing lengthwise through the casing g and pivotally connected at its front end to the upper end of an arm or standard I, which extends upwardly and rearwardly from the central portion of the lower bracket D, so that the rod is free to swivel laterally for accommodating itself to the oscillating movement of the upper jaw-plate. For this purpose the rod is preferably provided at its front end with an eye h', which engages with a hook i of the arm I.

J is a centering or return spring arranged in the casing g around the guide-rod h and bearing at its front end against the closed head of the casing and at its rear end against an adjusting-nut k, which engages with the screw-threaded rear portion of the guide-rod. This adjusting-nut is preferably provided with a sleeve or tubular extension k', which fits into the barrel g and forms with the latter a telescopic casing which completely encloses the spring and prevents binding or buckling of the same. The nut k forms a stationary rear abutment for the spring, and the latter therefore tends to hold the casing g, the yoke C, and the upper jaw-plate in their normal forward position. Upon pressing the upper plate rearwardly or oscillating it in a horizontal plane the spring is compressed, and upon releasing the plate the spring automatically returns the same to its normal position. The tension of the spring can be readily regulated as desired by screwing the nut k forwardly or backwardly on the guide-rod h.

If desired, the upper jaw-plate may be deprived of all movements except its vertical

one by screwing the adjusting-nut *k* against the rear end of the spring-casing *g*, so as to confine the casing against movement on the guide-rod *h*.

- 5 In order to reliably hold the upper plate in a raised or upright position and prevent the same from falling down accidentally and injuring the teeth or the cast, said plate is provided with an automatic catch, which interlocks with the lower bracket or base when the upper plate is raised to a position at right angles to the base. This catch preferably consists of a forwardly-facing lug or nose *l*, which is arranged on the under side of the 10 casing *g* and which is adapted to interlock with a lip *l'*, arranged at the lower rear portion of the arm *I*, as shown in Fig. 5. Upon swinging the upper plate to its upright position the beveled or rounded end of the locking-catch *l* rides over the lip *l'*, drawing the casing *g* and the yoke *C* downwardly on the guide-rod *h* and compressing the spring *J*, and as soon as the catch engages behind said lip the spring reacts and draws the yoke upwardly, thereby locking the upper plate. In order to release the locked plate, it is only necessary to depress the same sufficiently to disengage its locking-catch from the lip *l'*.

15 *M* represents thumb-pieces arranged at the ends of the yoke *C* on its front side and extending outwardly or laterally therefrom. These thumb-pieces permit the upper plate to be conveniently oscillated when testing the case for occlusion without exerting any 20 pressure upon the teeth, thus rendering the test more accurate.

25 The lower bracket *D* is provided with a post *n*, which is vertically adjustable on the base-standard *E*, so that the upper plate can be raised or lowered to accommodate casts of 30 different thicknesses. The standard is provided at its lateral edges with upright grooves or ways *o*, which receive the edges of the post *n*, and the standard is split or divided vertically, as shown at *o'*.

40 *p* is a transverse clamping-screw or bolt which passes through perforated lugs *p'*, formed on the front side of the standard on opposite sides of its slit and whereby the divided 45 portions of the standard are drawn together for tightly clamping the post *n* in the grooves of the standard. Upon loosening this bolt the upper plate can be adjusted vertically, and after affecting the adjustment the bolt is again tightened.

50 I claim as my invention—
1. The combination with the base or lower jaw-plate, of the upper jaw-plate and its yoke or bracket capable of a combined vertical and forward-and-backward movement, a guide

55 confined against longitudinal movement on the lower jaw-plate and provided at its rear end with an abutment, a spring-casing rigidly mounted on said yoke or bracket and sliding upon said guide, and a spring arranged in said casing and bearing at its rear end against said abutment, substantially as set forth.

2. The combination with the base or lower jaw-plate, of the upper jaw-plate and its yoke or bracket capable of a combined vertical and forward-and-backward movement, a guide-rod confined against longitudinal movement on the lower jaw-plate, a spring-casing sliding on said guide-rod, an adjusting-nut mounted on the rear portion of said rod and having a 70 tubular extension which enters said casing, and a spring arranged in said casing between said nut and the head of the casing, substantially as set forth.

3. The combination with the base or lower jaw-plate, having a bracket and an arm extending upwardly from said bracket and provided with a hook, of an upper jaw-plate and its yoke or bracket capable of a combined endwise and lateral movement on said base-bracket and carrying a rigid spring-casing, a guide-rod passing loosely through said casing and provided at its front end with an eye which engages with said hook and at its projecting rear end with an adjusting-nut, and a spring arranged in said casing and abutting at its rear end against said nut, substantially as set forth.

4. The combination with the base or lower jaw-plate, of the upper jaw-plate capable of 80 swinging vertically on the lower plate, and a catch whereby the upper plate is locked in its raised position, substantially as set forth.

5. The combination with the base or lower jaw-plate, of the upper jaw-plate capable of 85 a combined vertical and forward-and-backward movement on the lower plate and provided with a catch which is arranged to interlock with the base or lower plate when the upper plate is raised, and a spring which tends to shift the upper plate forwardly, substantially as set forth.

6. The combination with the base or lower jaw-plate, of the upper jaw-plate capable of 90 a combined lateral and endwise movement and having a yoke or bracket which is provided adjacent to its hinge with projecting thumb-pieces, substantially as set forth.

Witness my hand this 28th day of June, 1900.

THEO. G. LEWIS.
